UNITED STATES PATENT OFFICE.

JEFFERSON PALMER, OF CLARK, SOUTH DAKOTA, ASSIGNOR OF ONE-HALF TO FRANK G. BOHRI, OF CLARK, SOUTH DAKOTA.

EXPLOSIVE-ENGINE.

No. 864,253.

Specification of Letters Patent.

Patented Aug. 27, 1907.

Application filed February 28, 1907. Serial No. 359,865.

To all whom it may concern:

Be it known that I, JEFFERSON PALMER, a citizen of the United States, residing at Clark, in the county of Clark and State of South Dakota, have invented certain new and useful Improvements in Explosive-Engines; and I do declare the following to be a full, clear, and exact description of the invention, such as will enable others skilled in the art to which it appertains to make and use the same.

10 This invention relates to improvements in explosive engines.

The object of the invention is to provide a one-cycle, single cylinder engine having means for mixing and forcing air and gas into the combustion cylinder of the 15 engine.

A further object is to provide a motor of this kind which will be simple, strong and durable in construction, effective and reliable in operation and adapted for the use of gas, gasoline or alcohol.

20 With these and other objects in view, the invention consists of certain novel features of construction, combination and arrangement of parts, as will be more fully described and particularly pointed out in the appended claims.

25 In the accompanying drawings, Figure 1 is a side view of one side of the engine; Fig. 2 is a similar view of the opposite side; Fig. 3 is a top plan view; Fig. 4 is a vertical longitudinal sectional view through the combustion cylinder of the engine; Fig. 5 is a similar view 30 through the air and gas mixing chamber; Fig. 6 is a horizontal sectional view taken through the center of the combustion cylinder and mixing chamber; Fig. 7 is a vertical cross sectional view through the combustion cylinder and mixing chamber on a line with the 35 inlet and exhaust valves at the forward end of the same; Fig. 8 is a similar view taken on a line with the inlet and exhaust valves at the rear end of the engine; and Fig. 9 is a detail view of one of the air and gas controlling valves.

40 Referring more particularly to the drawing, 1 denotes the engine, which is provided with a combustion cylinder, 2, and an air and gas mixing chamber, 3, said combustion cylinder and mixing chamber being arranged parallel with each other, and surrounded by a water jacket, 4, to which is connected water inlet and outlet pipes, 5 and 6, which connect with a water supply tank (not shown).

45 Slidably mounted in the combustion cylinder, 2, is a piston, 7, having a piston rod, 8, which projects through and is slidably mounted in a stuffing box, 9, arranged on the forward head of the cylinder, as shown. The outer end of the piston rod, 8, is connected to a cross head, 10, which is slidably mounted in a suitable 50 guide frame, 12, arranged on the base of the engine.

Secured to the piston rod, 8, between the cross head, 10, and the forward end of the engine, is a cross head, 13, which is connected by a pair of pitman rods, 14, to the crank shaft, 15, journaled in suitable bearings on the forward end of the base of the engine, as shown.

55 Slidably mounted in the mixing chamber, 3, is a piston, 16, having a piston rod, 17, which works through the forward head of the cylinder, the outer end of said piston rod being slidably mounted in a suitable bearing, 18, arranged on the base of the engine. Secured to the piston rod, 17, between the bearing, 18, and the end of the engine cylinder, is a cross head, 19, to which is pivotally connected the inner end of a pitman rod, 20, the outer end of which is loosely connected with the crank shaft, 15, by means of which the piston rod, 17, and piston, 16, are reciprocated simultaneously with the 60 movement of the piston 7, in the combustion cylinder.

65 Arranged near the forward end of the mixing chamber is an air inlet valve, 21, which is normally held in a closed position by means of a coiled spring, 22. In the rear of the mixing chamber is arranged an air 70 inlet valve, 23, which is normally held in closed position by a coiled spring, 24.

75 Connected with the mixing chamber, 3, substantially midway between its end, is a gas supply pipe, 25, which is connected to a gas tank, or other gas supply (not shown). The gas supply pipe, 25, is provided with a cut-off valve, 26, which is connected to a suitable controlling mechanism or governor (not shown), but by means of which the flow of gas to the mixing chamber is automatically controlled, thereby 80 enabling the engine to maintain a fixed speed under varying load conditions.

85 At the forward end of the combustion chamber is an air and gas inlet port, 27, while at the rear end of the combustion cylinder is an air and gas inlet port, 28, said ports, 27 and 28, communicating with the front and rear ends of the mixing chamber. In the end of the port, 27, adjacent to the combustion cylinder is arranged a check valve, 29, which is normally held in a closed position by a spring, 30. In the end 90 of the rear port, 28, adjacent to the combustion cylinder, is a check valve, 31, which is normally held in a closed position by a coiled spring, 32. The check valves, 29 and 31 are adapted to be opened by the pressure of the mixed gas and air from the mixing 95 chamber to admit said gas and air into the opposite ends of the combustion cylinder. The end of the port, 27, adjacent to the mixing chamber is adapted to be opened and closed by means of a controlling valve, 33, which is slidably mounted in a suitable 100 seat, 34, formed in the side wall of the mixing chamber. The valve, 33, is provided with a forwardly projecting stem, 35, having arranged thereon a coiled spring, 36.

The stem, 35, is adapted to work in a hollow lug, 37, mounted in the front head of the cylinder, said valve being normally held in position to close the port, 27, by means of the coiled spring, 36. On the inner end 5 of the valve, 33, is arranged an inwardly projecting offset stem, 38, which is adapted to be engaged by the piston, 16, at each forward stroke of the engine, thereby operating said valve to open the port, 27, and allow the mixed air and gas in this end of the 10 mixing chamber, which is compressed by the forward movement of the piston, 16, to enter the port, 27, and open the check valve, 29, and pass into the forward end of the combustion cylinder, where it is ignited by a suitable sparking mechanism hereinafter 15 described.

In the rear end of the mixing chamber is arranged a controlling valve, 39, said valve being slidably mounted in a seat, 40, formed in the side wall of the mixing chamber around the end of the port, 28. The 20 valve, 39, is provided with a rearwardly projecting stem, 41, which is adapted to work in a tubular plug, 42, arranged in the rear head of the engine cylinder. On the stem, 41, is arranged a coiled spring, 43, by means of which the valve, 39, is normally held in position to close the port, 28. The forward end of the 25 valve, 39, is provided with an offset rearwardly projecting stem, 44, which is adapted to be engaged by the piston, 16, in the mixing chamber when said piston moves upwardly on the inner or rear stroke 30 of the engine, thereby operating the controlling valve, 39, to open the port, 28, and permit the mixed air and gas which has been compressed in this end of the chamber by the rearward movement of the piston, 16, to pass through said port and pass the check valve 35 31, into the rear end of the combustion chamber where the mixed air and gas is ignited by a suitable sparking mechanism, hereinafter described.

In the outer wall of the combustion cylinder, adjacent to the forward end thereof, is arranged an exhaust valve, 45, which is provided with an outwardly projecting stem, 46, and is firmly held in a closed position by a coiled spring, 47. The valve, 45, is adapted to be opened at the proper time to discharge the products of explosion from the forward end of the 45 combustion cylinder, by means of an operating lever, 48, which is pivotally mounted at its rear end in a bracket, 50, secured to the rear end of the engine cylinder, and is held in position midway between its ends by a guide pin, 51, projecting from the side of 50 the engine cylinder. On the pin, 51, is arranged a coiled spring, 52, by means of which the lever, 48, is normally held in inoperative position. The lever, 48, is operatively connected to the stem, 46, of the valve, 45, by means of a bracket, 53. The forward end of 55 the lever, 48, is adapted to operate at the proper time to open the exhaust valve, 45, by means of an operating wheel, or disk, 54, which is fixedly mounted on the end of the crank shaft, 15, and is provided, on its side with a cam projection, 55, which, as said disk or 60 wheel is turned by the crank shaft, is adapted to be brought into engagement with the forward end of the lever, 48, thereby forcing the same inwardly against the tension of the spring, 52, and causing said lever to open the exhaust valve at the forward end of the 65 combustion chamber.

In the outer wall of the combustion cylinder, adjacent to the rear end thereof, is arranged a rear exhaust valve, 56, having an outwardly projecting stem, 57, on which is arranged a coiled spring, 58, adapted to normally hold the valve, 56, in a closed position. Connected to 70 the outer end of the stem, 57, is a valve operating lever, 59, which is pivotally mounted in a bracket, 60, secured to the base of the engine. The forward end of the lever, 59, extends to a position adjacent to the outer side of the operating disk, 54, on the crank shaft, 15, and is 75 adapted to be engaged by a cam projection, 61, on said outer side of the disk in position to be engaged with the forward end of the lever, 59, to operate the same and thereby open the exhaust valve, 56, at the proper time to discharge the products of explosion from the rear end 80 of the combustion cylinder.

Arranged in the forward head of the engine cylinder is a sparking plug, 62, which is connected by a conducting wire, 63, to a binding post, 64, on the engine cylinder, said binding post being in electrical communication with a contact plate, 65. The inner end of the 85 sparking plug, 62, is adapted to co-act with the opposing pole, 66, of the electric circuit so that when a current of electricity is passed through said circuit, a spark will be produced to ignite the mixed air and gas in the forward 90 end of the combustion cylinder.

Arranged on the rear head of the engine cylinder is a rear sparking plug, 67, which is connected by an electric conducting wire, 68, to a binding post, 69, arranged on the engine cylinder, said post 69, being in electrical 95 connection with a contact plate, 70. The inner end of the 100 sparking plug, 67, projects into the rear end of the combustion chamber, and is adapted to co-act with the opposing pole, 71, of the electric circuit at this end of the cylinder, whereby when a current of electricity is passed through said circuit a spark will be produced to ignite the explosive mixture in this end of the combustion cylinder.

The poles, 66, and 71, are in electrical connection with the body of the engine to which is connected one 105 of the main conducting wires, 72, of the electric circuit. The opposite main conducting wire, 73, of the circuit being connected to a cut-out switch, 74, which is here shown in the form of a spring metal plate secured to one side of the engine cylinder. The free end of the switch 110 plate, 74, is offset and is adapted to normally engage a switch, 75, which is here shown in the form of a metallic disk pivotally mounted on the side of the engine cylinder. The switch, 75, is provided on its edge with a radially projecting contact lug, 76, which, when the 115 switch, 75, is oscillated, is adapted to be brought into engagement with one or the other of the contact plates, 65 or 70, thereby completing the electric circuit, and causing a spark to be produced in one end or the other of the combustion cylinder. Connected with the 120 switch disk, 75, is an operating rod, 77, which is slidably mounted in suitable guides arranged on the side of the engine cylinder. The outer end of the rod 77 is provided with an elongated loop or slot, 78, by means of which said outer end of the rod is loosely connected to a wrist pin, 79, on the cross head, 19, on the piston rod, 17, whereby when said piston rod and cross head are reciprocated, the switch disk, 75, will be oscillated to alternately bring the lug, 76, into communication with the contact plates, 65 and 70, to complete the electric 125 130

circuit to first one and then the other of the electric connections between the binding posts, 64, and 69, to the sparking plugs at the opposite ends of the combustion cylinder to cause the same to produce a spark at the proper time.

In order that the electric circuit may be entirely cut off from the engine to quickly stop the operation of the same, I provide a cut-out lever, 80, which is pivotally mounted at its lower end on one side of the engine cyl-

- 10 inder and is adapted to work at its upper end between the cut-out switch plate, 74, and the adjacent side of the engine cylinder, whereby when said lever is pushed rearwardly, the wedging action of the same will force the cut-out switch plate, 74, outward, thereby disengaging the off-set forward end thereof from the switch disk so that the circuit through the main contact wire, 73, will be broken, thereby stopping the engine. The cut-out lever, 80, has preferably connected to its upper end an operating rod, 81, which is slidably mounted in
- 15 guides on the engine cylinder, whereby said lever may be conveniently operated by the engineer. It will be understood that when the operating lever, 80, is swung inward that the cut-out switch plate, 74, will by reason of its spring metal construction engage the switch disk,
- 20 75, thus connecting the main electrical supply wire, 73, to said disk.

From the foregoing description, taken in connection with the accompanying drawings, the construction and operation of the invention may be readily understood

30 without requiring a more extended explanation.

Various changes in the form, proportion and the minor details of construction may be resorted to without departing from the principle or sacrificing any of the advantages of this invention as defined in the appended claims.

Having thus described my invention, what I claim as new, and desire to secure by Letters Patent, is:

1. An explosive engine having a combustion cylinder and a mixing chamber, a piston in said combustion cylinder adapted to be reciprocated by the force of the explosions therein, a piston in said mixing chamber adapted to be operated by the piston in said combustion cylinder to draw air and gas into said mixing chamber and to force the same into said combustion cylinder, inlet and exhaust valves arranged in said combustion cylinder, controlling valves in said mixing chamber, whereby the air and gas mixture therein is admitted to said inlet valves, and a

- 95

sparking mechanism to ignite the gas mixture in said combustion cylinder, substantially as described.

2. An explosive engine having a combustion cylinder and a mixing chamber arranged in parallel relation, a piston in said combustion cylinder adapted to be reciprocated by the force of the explosions therein, inlet valves in said combustion chamber, controlling valves to co-act with said inlet valves, whereby the gas mixture in said mixing chamber is admitted first to one end and then to the other of said combustion chamber, an automatically operated sparking mechanism whereby the gas mixture is alternately ignited in the opposite ends of said combustion cylinder, an exhaust valve in each end of said cylinder, operating levers connected with said exhaust valves, and means whereby said levers are actuated at the proper time to open said valves, substantially as described.

3. An explosive engine having a combustion cylinder and a mixing chamber arranged in parallel relation thereto, a piston in said cylinder and chamber, piston rods connected to said pistons, a crank shaft connected with said piston rods and operated by the piston in said combustion cylinder, air inlet valves, a gas supply pipe connected with said mixing chamber, inlet and exhaust valves in said combustion chamber, controlling valves in said mixing chamber adapted to be operated by the piston therein to admit the gas mixture to first one and then the other of said inlet valves, pivotally mounted operating levers connected to said exhaust valves, and an operating disk on said crank shaft whereby first one and then the other of said levers are actuated to alternately open said exhaust valves, substantially as specified.

4. An explosive engine having a combustion cylinder and a mixing chamber arranged in parallel relation, a water jacket surrounding said cylinder and chamber, pistons in said cylinder and chamber, piston rods connected to said pistons, a crank shaft connected with said rods and operated by the piston in said combustion cylinder where by motion is imparted to the piston in said mixing chamber, air inlet valves and a gas supply pipe connected with said mixing chamber, inlet and exhaust valves in said combustion chamber, controlling valves in said mixing chamber adapted to be operated by the piston therein to admit the gas mixture to first one and then the other of said inlet valves, exhaust valves arranged in said combustion cylinder, pivotally mounted operating levers connected to said exhaust valves, an operating disk on said crank shaft, and cam projections on the opposite sides of said disk to engage said levers and thereby open first one and then the other of said valves at each revolution of the crank shaft, substantially as described.

In testimony whereof I have hereunto set my hand in presence of two subscribing witnesses.

JEFFERSON PALMER.
